UNITED STATES PATENT OFFICE.

HENRY HUNT, OF GREENVILLE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 13,664, dated February 27, 1883.

Application filed January 25, 1883. Term of patent 3½ years.

To all whom it may concern:

Be it known that I, HENRY HUNT, of Greenville, in the county of Hudson and State of New Jersey, have invented a new and original 5 Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design. The ground is, in irregular portions, either plain or ornamented by a small diagonal figure, as 15 shown, with a conspicuous Greek-letter ornament running brokenly over it and forming part of it. On this ground is disposed a system of flower groups consisting of various scattered groups of flowers, leaves, and bud-sprays, all as shown in the photograph.

I claim—

1. The design for a ground for a carpet, consisting of the ground, substantially as shown and described.

2. The design for a carpet, consisting of the system of flower groups, substantially as shown and described.

3. The design for a carpet, consisting of the system of flower groups and the ground, substantially as shown and described.

HENRY HUNT.
